CLAIM

The ornamental design for a beverage container, as shown and described.

DESCRIPTION

FIG. 1 is a top perspective view of a first embodiment of a beverage container showing our new design;
FIG. 2 is a bottom perspective view thereof.
FIG. 3 is a front elevational view thereof.
FIG. 4 is a right side elevational view thereof.
FIG. 5 is a left side elevational view thereof.
FIG. 6 is a rear elevational view thereof.
FIG. 7 is a top plan view thereof.
FIG. 8 is a bottom plan view thereof.
FIG. 9 is a top perspective view of a second embodiment thereof.
FIG. 10 is a bottom perspective view thereof.
FIG. 11 is a front elevational view thereof.
FIG. 12 is a right side elevational view thereof.
FIG. 13 is a left side elevational view thereof.
FIG. 14 is a rear elevational view thereof.
FIG. 15 is a top plan view thereof; and,
FIG. 16 is a bottom plan view thereof.
The broken lines in the drawings depict portions of the beverage container that form no part of the claimed design.
